United States Patent Office

Des. 192,210
Patented Feb. 13, 1962

192,210

DISPOSABLE SANDAL

John T. Webster, 11131 Maple St., Los Alamitos, Calif.,
and Ernest L. Julian, 13231 Cannery St., Garden
Grove, Calif.

Filed Oct. 3, 1961, Ser. No. 66,956

Term of patent 14 years

(Cl. D7—7)

I claim:

The ornamental design for a disposable sandal, substantially as shown.
